Primary Examiner — Jae Liang
Assistant Examiner — Tia Ruth-Renee Polidori(57) **CLAIM**

The ornamental design for a car fridge, as shown and described.

DESCRIPTION

FIG. 1 is a perspective view of a car fridge showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of our new design for a car fridge in a configuration of use;

FIG. 10 is an enlarged view of portion 10 shown in FIG. 1;

FIG. 11 is an enlarged view of portion 11 shown in FIG. 2; and,

FIG. 12 is an enlarged view of portion 12 shown in FIG. 2. The dash-dash broken lines in the drawings depict portions of the car fridge that form no part of the claimed design and the dot-dash broken lines in the drawings depict partial view indicia that forms no part of the claimed design.

1 Claim, 12 Drawing Sheets(58) **Field of Classification Search**
